UNITED STATES PATENT OFFICE.

FRANK S. LEWIS, OF BALTIMORE, MARYLAND.

AUTOMATIC SWITCH.

SPECIFICATION forming part of Letters Patent No. 699,197, dated May 6, 1902.

Application filed February 26, 1902. Serial No. 95,698. (No model.)

To all whom it may concern:

Be it known that I, FRANK S. LEWIS, a citizen of the United States, residing at Baltimore, in the State of Maryland, have invented 5 new and useful Improvements in Automatic Switches, of which the following is a specification.

My invention relates to automatic railway switches adapted to be operated by the contact of the flange of a wheel with the switch-point.

The invention consists of the combination, with a main rail and pivoted switch-point, of a guard-rail interposed between the main rail 15 and switch-point and a crank-shaft having a worm extending through a slot in the switch-point.

The invention further consists of the novel construction and arrangement of the guard-rail and the detail features hereinafter fully described and claimed, in connection with the accompanying drawings, which form a part of this specification, and in which—

Figure 1 is a plan view of a railway-switch 25 embodying the invention. Fig. 2 is a vertical section of the same, and Fig. 3 is a detail side elevation of the guard-rail.

The reference-numerals 1 and 2 designate the rails of the main track, 3 one rail of a 30 siding, and 4 the pivoted switch-point.

5 designates a crank-shaft, one end of which is supported in a bearing 6 of the rail 1, while its opposite end 7 is in the form of a worm and extends through a slot 8, formed 35 in the switch-point. The crank 9 of the shaft extends through a loop or keeper 10, depending from a guard-rail 11, pivotally held at one end between the rail 1 and the switch-point 4. The free end 12 of the guard-rail is oppositely beveled, as best shown in Fig. 2, to 40 guide the passage of the wheels thereover.

The movement of the switch-point by the contact therewith of the wheel-flange oscillates the crank-shaft through the medium of 45 the worm 7, and the connection of the crank 9 with the guard-rail serves to raise and lower

the guard-rail according to the direction of movement of the switch-point.

While the construction is believed to be a practical embodiment of the invention, I would have it understood that I reserve the right to make all such modifications and variations in the details as will not depart from the essential features of the invention as defined in the following claims. 55

I claim—

1. In an automatic switch, the combination with a main rail, and a switch-point, of a crank-shaft extending through said rail and switch-point, and formed with a worm working through a slot in the switch-point, and a guard-rail interposed between the main rail and switch-point, and adapted to be raised and lowered by the movement of the crank-shaft. 60

2. In an automatic switch, the combination with a main rail, and a switch-point, of a crank-shaft extending through said rail and switch-point, and formed with a worm working through a slot in the switch-point, a beveled guard-rail interposed between the main rail and switch-point, and having its free end oppositely beveled, and a connection between said crank-shaft and guard-rail to raise and lower the latter through the movement of the crank-shaft. 70

3. In an automatic switch, the combination with a main rail and a switch-point, of a crank-shaft extending through said rail and switch-point, and formed with a worm working through a slot in the switch-point, a guard-rail located between the main rail and switch-point pivotally secured at one end and oppositely beveled on the upper surface of its free end, and a keeper depending from the guard-rail through which the crank of the shaft extends. 80

In testimony whereof I affix my signature in presence of two witnesses.

FRANK S. LEWIS.
